UNITED STATES PATENT OFFICE.

ARTHUR E. JONES, OF NEW BRITAIN, CONNECTICUT, ASSIGNOR OF ONE-HALF TO CHARLES J. WHITE, OF SAME PLACE.

SUSPENDER-BUCKLE.

SPECIFICATION forming part of Letters Patent No. 499,836, dated June 20, 1893.

Application filed March 15, 1893. Serial No. 466,054. (No model.)

To all whom it may concern:

Be it known that I, ARTHUR E. JONES, a citizen of the United States, residing at New Britain, in the county of Hartford and State of Connecticut, have invented certain new and useful Improvements in Suspender-Buckles, of which the following is a specification.

My invention relates to improvements in suspender buckles, and the objects of my improvement are simplicity and cheapness of construction and general efficiency of the article.

In the accompanying drawings: Figure 1 is a front elevation of my suspender buckle with a ring and suspender straps hooked thereon. Fig. 2 is a side elevation of the same. Fig. 3 is a detached plan view of my buckle frame. Fig. 4 is a front elevation of my buckle as applied to a suspender, together with the ring of the suspender straps illustrating the manner of attaching and detaching the same to the hook of the buckle. Fig. 5 is a front view of the tongue with part of the frame broken away, and Fig. 6 is an elevation showing my buckle in a modified form for use as a slide.

I form the buckle frame A of wire, the same being doubled upon itself, as at 6, and the wire so doubled again folded upon itself as at 7 to form a hook to receive the ring 8 of the suspender straps 19. The two members of the wire are then spread laterally away from the point of the hook, then bent forward and back to form the guard 9 near the upper end of the hook, then upwardly to the cross bar of the frame which is formed of reversed curves 10 and 11 and short straight portions on each side from which it is bent backward at right angles to the main front of the frame 40 and its ends brought toward each other, as at 12, to form the axial support for the buckle tongue 13. This buckle tongue is formed of sheet metal with a plate like handle 14 and pointed bar 13, the same being bent wholly or partially around the pivotal support 12 of the frame. I prefer to employ the strengthening tube 15 placed upon the tongue support 12 within the angle of the buckle tongue and its handle as shown in Fig. 2. The end portions of said tube 15 may be embraced by the lugs 16 formed near the side edges of the

buckle tongue, and the middle portion of said tube embraced by means of the lug or flap 19 cut from the handle 14 and rolled over said tube as best shown in Figs. 2 and 5. I also prefer to give a neat finish and strengthen the handle by the bead 18 as shown in Fig. 5.

The points on the buckle tongue 13 are so spaced with reference to the reverse bends in the cross bar of the frame as to come within the space formed in said bends as shown in Fig. 1.

My buckle will be secured to the suspender B by passing the same between the buckle tongue and the cross bar of the frame, when the handle 14 is turned outwardly, and then securing the same by turning the handle back to engage the suspender between the points of the buckle tongue and cross bar. The ring 8 of the straps 9 can be attached and detached from the hook when it is in an edgewise position as shown in Fig. 4, but it is prevented from being detached when it lies flat, as shown in Figs. 1 and 2, by the stop shoulders or guard 9 toward the upper part of the hook and can only be detached from the hook by turning it more or less edgewise.

In Fig. 6 I have shown substantially the same buckle as applied to the suspender, but with the hook omitted and the loop 17 substituted for said hook, the said loop being designed to receive the free end of the suspender and the buckle arranged to slide along the body of the suspender to adjust its length.

I claim as my invention—

1. The herein described suspender buckle consisting of a frame having the cross bar provided with transverse bends, an axial support for the tongue in the rear of said cross bar and a tongue provided with points arranged opposite the spaces formed by said transverse bends, substantially as described and for the purpose specified.

2. In a suspender buckle, the hook for receiving the ring 8, having the stop shoulders 9 upon each side thereof and side members extending upwardly therefrom to the cross bar of the frame, substantially as described and for the purpose specified.

3. In a suspender buckle, the strengthening tube 15 and the combined tongue and handle with the lug or flap 19 cut and bent from the

handle around the middle portion of said tube, substantially as described and for the purpose specified.

4. In a suspender buckle, the strengthening tube 15 and the combined tongue and handle with the lugs 16 near the side edges of the tongue bent around said tube near its ends, substantially as described and for the purpose specified.
5. In a suspender buckle the strengthening

tube 15 and the combined tongue and handle with the lug or flap 19 cut and bent from the handle around the middle portion of said tube, and the lugs 16 bent around said tube near its ends, substantially as described and for the purpose specified.

ARTHUR E. JONES.
